PLATE OR SIMILAR ARTICLE

William M. Curtis, Corning, N.Y., assignor to Corning Glass Works, Corning, N.Y., a corporation of New York

Filed Mar. 8, 1965, Ser. No. 84,125

Term of patent 14 years

(Cl. D44—15)

FIG. 1

FIG. 2

FIGURE 1 is a top plan view of a plate of conventional configuration, showing my new design.

FIGURE 2 is an enlarged fragmental cross-sectional view in elevation taken along line 2—2 of FIGURE 1 illustrating the texture of the design.

My design for a plate or similar article is characterized by a plurality of spaced annular grooves having color and surface character contrasting with that of the remainder of the body surface, in the arrangement and having the configurations substantially as shown.

I claim:

The ornamental design for a plate or similar article, as shown and described.
